*Primary Examiner—Alan P. Douglas**Assistant Examiner—Antoine D. Davis**Attorney, Agent, or Firm—Dowell & Dowell*[57] **CLAIM**

The ornamental design for a milling head for wood-working, as shown and described.

DESCRIPTION

FIG. 1 is a front perspective view of a milling head for woodworking showing my new design;

FIG. 2 is a front elevational view thereof; and,

FIG. 3 is a left side elevational view, a view taken from the right side being a mirror image thereof.
